UNITED STATES PATENT OFFICE

JOHN J. MURPHY, OF CINCINNATI, OHIO

ANTISLIP RUBBER HEEL

Application filed December 28, 1927. Serial No. 243,147.

This invention relates to new and useful improvements in rubber heels and has for an object the provision of a structure wherein added resiliency of the heel and greater protection against accidental slipping are attained.

Another object is to provide a structure of this kind which is inexpensive of manufacture and very durable.

10 Another object is to provide a structure which is adapted to the facile reception and removal of a metallic ice creeper attachment.

Another object is to provide a simple and easily applied ice creeper for detachable connection with heels.

These and other objects are attained by the means described herein and disclosed in the accompanying drawings, in which:

20 Fig. 1 is a bottom plan view of an anti-slip rubber heel of the invention.

Fig. 2 is a view taken on line 2—2 of Fig. 1.

Fig. 3 is a view similar to Fig. 2 but showing an ice creeper of the invention operatively associated with the heel.

Fig. 4 is a perspective view of the detachable ice creeper of the invention.

Fig. 5 is a cross sectional view on line 5—5 of Fig. 4.

30 The heel of this invention is formed by providing a rubber heel 9 with narrow transverse slots 10 extending from the bottom 11 of the heel upwardly to a depth usually determined by the location of the usual embedded metallic washers 12. In the preferred form the heel is preferably saw-slotted so that the slots 10 are narrow and relatively deep and are so spaced as to present on the bottom of the heel a plurality of transverse 40 bars 13 closely spaced, but adapted to yield either forwardly or rearwardly of the foot of the wearer. The upper body portion of the heel is adapted to be fixed securely and non-yieldably to the usual leather heel, (not shown) of a shoe by means of nails or screws passing through the metal washers 12. In

45 use the joint action of the non-yielding portion 14 and the flexible and resilient bars 13 provide a surprisingly soft, velvety or pneumatic sensation to the wearer, an effect which

is comfortable to the foot and very restful to the wearer. Any of the bars 13 may yield or slightly flex toward or away from an adjacent bar under the impact of the weight of the user. This results in a gripping action 55 of the bottom or wearing face of the bars which effectively prevent slipping upon a smooth slippery surface such as wet metal, stone or the like.

The relative movement of the bars 13 contrary to possible expectation, does not permit of the accumulation of compacted dirt in the narrow slots 10. It has been found in practice that these slots remain substantially free of accumulated matter.

65 In order to adapt the heel of the invention to the use of those who, because of infirmity or fear, resort to ice creepers in the winter season, there is provided in the body 14 a transverse bore 15 which communicates along 70 one side with one of the slots 10. A removable ice creeper is formed by providing a metallic blade 16 embedded in or formed integrally with a rod 17. The rod is of a diameter such that it fits snugly in the bore 15 and the blade is of a thickness substantially equal to the width of one of the slots 10. The blade extends radially of the longitudinal axis of the rod and is of a width slightly in excess of the depth of the slot so that it may protrude beyond the bottom face of the heel. A suitable knob 18, provided in the present embodiment by a short bent portion on the rod, 75 provides handle means which closely hugs the side of the heel and obviates the possibility of becoming an impediment to walking or a means upon which wearing apparel might become caught. A slight extension 19 on the opposite end of the rod protrudes just enough beyond the opposite side of the body 80 of the heel to permit pressure thereon with the sole of the other shoe, or with the finger, or with a suitable implement whereby to dislodge the knob 18 sufficiently to permit grasping with the fingers to remove the ice creeper 85 from the heel.

90 The ice creepers are much smaller than the heretofore used kindred device and may be applied and removed in a moment of time without difficulty.

What is claimed is:

1. In a device of the class described the combination of a heel having a transverse bore through the body thereof and a restricted slot communicating with the bore and opening onto the bottom face of the heel, and a removable ice creeper comprising a rod and an integral blade extending radially therefrom, the rod and blade slidably positioned in the bore and slot respectively for retaining the blade in an operative position projecting beyond the bottom of the heel.
- 10 2. In a device of the class described the combination of a rubber heel having narrow and widely spaced transverse slots therein, a transverse bore through the heel communicating along one side with one of the slots, and a metallic ice creeper removably inserted in said bore and its communicating slot.
- 15 3. In a device of the class described the combination of a heel having a transverse bore and a restricted communicating slot extending to the bottom face of the heel, an ice creeper comprising a blade in the slot and frictionally retained therein, and means on one edge of the blade disposed in the bore to preclude accidental separation of the ice creeper and heel.
- 20 4. In a device of the class described the combination with a heel having a transverse bore and a communicating slot extending radially of the bore, of a removable ice creeper comprising a portion for entry into the bore, a blade adapted to extend through the slot and project beyond the bottom face of the heel, and means comprising a curved projection on the portion in the bore for removing the creeper from the heel.

In testimony whereof, I have hereunto subscribed my name this 22nd day of December, 1927.

JOHN J. MURPHY.
